CATHODE RAY TUBE

Pierre Marie Gabriel Toulon, Puteaux, France

Application July 9, 1936, Serial No. 89,707
In France July 9, 1935

2 Claims. (Cl. 178—7.5)

This invention relates to cathode ray tubes, and in particular, to cathode ray tubes adapted for the projection of high intensity images.

The invention covers a new method which permits of transforming into a very intensive luminous spot the beam of cathode-ray oscilloscope, and especially of projecting on a screen the image resulting from the modulation and from the displacement of the beam by the deflecting electrodes during the scanning.

The invention can be particularly applied to projection apparatus for television purposes, whose scanning device is a cathode ray tube. It consists in using an auxiliary and powerful light source and in causing the luminous beam emanating from it to strike on the surface that receives at the same time the cathode ray beam from the cathode ray tube, so as to modulate locally the luminous intensity, according to the intensity of the electron beam; and in causing to appear on the screen an enlarged and luminous image of the televised subject.

The process according to the invention of locally modulating the luminous beam by the impact of the electronic beam may have several variants:

The negative charges carried by the beam can be utilized directly through the conductivity of the wall by means of conducting rods fixed within the insulating mass of the latter, or indirectly by influence effect.

It is also possible to utilize the electronic radiation (Lenard rays) or the electromagnetic radiation (X-rays, ultra violet rays, etc.) resulting from the impact of the beam on the anticathode.

In order to modulate the luminous beam one can avail one's self of the displacement or the depositing of material particles on the wall electrified by the electronic beam (the particles consisting of sulphur, red lead, etc.) or of the modification of the optical properties of certain substances (quartz, Cellophane, etc.) or also of the releasing of gaseous bubbles, as well as of electrolytical depositing, cataphoresis, etc. According to the invention, one can use—always starting

from the electronic beam—either the deposited electric charges or the current which has been locally engendered, or also the electromagnetic radiation, in order to control the illumination produced by the auxiliary light source. That control can be accomplished by modifying the opacity or the plane of polarization, or the respective position of the substances that are suitably distributed on the surface, etc.

Several figures attached to this specification

explain the object of the invention and physical embodiments of it in some particular instances.

The drawing shows in Fig. 1 a physical embodiment in which the electrified charges produced by the cathode beam serve to rotate the plane of polarization of the light;

Fig. 2 shows another realization in which the electric charges cause the displacement of silvered movable leaves; and

Fig. 3 represents another physical embodiment in which the depositing of materials, or electrochemical phenomena, etc., are utilized. All these figures have been given only by way of examples.

It is evident that any system which comprises in combination a system of scanning by means of a cathode beam, an auxiliary light source, and a local modulation of the light beam by the cathode beam, in order to reproduce an image of the source on a screen—which image is modulated according to the intensity of the cathode beam—comes within the scope of the invention covered by the present patent.

Certain substances such as Cellophane, quartz, mica, etc., have the property of rotating the optical plane of polarization when an electric potential is applied between their two surfaces. This property is used for bringing about the projection of a television image on a large screen (for instance by means of the device described in Fig. 1). The electron gun 1 comprises a control grid connected to the radio receiving set, and the deflecting plates 3 and 4 insure the scanning of the beam in synchronism with the transmitter.

The screen which ordinarily is metallized and provided with a transparent fluorescent substance is here made up of a very large number of small conducting squares, 7, that are insulated one from the other and arranged on the optically variable insulating substance 6. A thin metal film 5, provided on the back of that substance, fixes the potential and has the effect of creating a high electric field as soon as a charge is deposited on any one of the small squares 7.

The scanning of the modulated cathode beam has thus the effect of introducing on the different successive squares, such as 7, variable negative charges, and these deposited charges modify the plane of polarization of the substance facing them. A very powerful light source 12 which is polarized by the system 13 illuminates the substance 6. By means of the lens 11 the light rays are then concentrated on the objective 16 and the nicol or other prisms 14. The thickness of the substance 6 and the positions of the nicols 13 and 14 are selected in such a manner that no light

will pass unless a charge is deposited on 7. In other words, the objective 16 transmits no light on the projection screen. On the other hand, when the apparatus is operating, charges will be deposited at 7 as a result of the influencing of grid 2 when the set is receiving, and these charges will reproduce the instantaneous image transmitted by the sender. The locally variable rotation of the plane of polarization of layer 6 permits 10 reproducing on the screen a very luminous and enlarged image of the televised object or person. The layer 6 may be made from Polaroid as is well known in the art.

It is very easy to realize that this image could 15 not, in that shape, be constantly mobile, for the electrons transmitted by the electron gun tend always to settle in the small squares represented by 7. In order to insure automatically the discharge at the end of a certain time, for instance 20 at the end of each image i. e. every twenty-fifth of a second, it is necessary to bring abruptly to each one of these little squares positive charges or, what amounts to the same, to remove abruptly from these squares several electrons, in order to bring them back to the neutral state or, more 25 exactly, to the potential of the electrode 5.

According to the invention, each one of the small elementary squares is itself covered with a photo-emissive substance (for instance, a substance preferably sensitive to ultra-violet radiation, such as potassium, strontium, magnesium, etc.).

At the end of the scanning of each image, for 35 instance, the discharge of the small squares is automatically insured by operating in the following manner: A gaseous discharge tube such as is generally used to produce saw tooth wave energy for the scanning of the images also causes, upon discharging, a mercury tube to light up (one comprising quartz for instance) or actuates by 40 relay means any other appropriate source of light that will furnish a light extremely rich in actinic rays. By means of a system 10 to concentrate the light, the various elementary cells 7 are enabled to emit electrons, provided their potential is high, that is to say, if they are charged. A grid 8 to 45 which a voltage is applied which is slightly higher than that of wall 5 during the operation captures the electrons and brings thus instantaneously all the little squares 7 to the common basic potential.

In this manner the apparatus is freed from all the preceding image charges and is now in a position to receive new image charges again, by 55 virtue of the scanning of the modulated beam, and to project a new image on the screen.

In conformity with Fig. 2, it is possible to utilize instead of the cathode rays 20 properly speaking that emanate from the electron gun 19 within 60 the tube, the electrified charges (Lenard rays) that leave it through a window of thin metal, for instance an aluminum foil supported by a grid.

The back of the oscillograph is then made up of an enclosure 3 containing a rarefied gas. A 65 metal grid 21 supports the very thin aluminum foil 22 that separates the cathode-ray oscilloscope (which is highly evacuated) from the enclosure containing the rarefied gas 23.

The Lenard rays impinge on the small elementary electroscopes 25 that are supported by an insulating grid 24, and bring about their deviation. If necessary, another conducting grid with a fixed potential, grid 26, may be made to strengthen the field thus created near these 70 electrometers.

The inclination of the foils of the various electroscopes is variable and the elementary reflecting surfaces have the effect of transmitting through the objective 29 a variable quantity of light that originates from the light source 28. A 5 lens or other optical system 27 is placed in register with the light beam to improve the efficiency.

At the end of the scanning, the automatic discharge of the different electroscopes is accomplished by means of the ionization of the gas in 10 the enclosure 23. To this end, two electrodes 17 and 18 are provided, and a high potential difference is abruptly impressed between them (under the influence of the scanning or synchronizing pulse) this voltage application resulting in a 15 spark discharge.

It is possible also to insure the projection on the screen in conformity with the invention by materializing the cathode image by means of deposits of very fine, dust-like particles. As is 20 shown in Fig. 3, the back of the oscillograph may be made to consist of a material which is sufficiently conducting, so that the electrified charges 30 will pass through it. A grid 31 prevents the charges deposited on the walls from disturbing 25 the field in the tube. If at the back of the apparatus in wall 33 a mixture of electrified dust is kept in constant agitation, for instance, flowers of sulphur and minium, one may, through electrostatic influence, obtain the deposit of that dust 30 mixture on the electrified points (Hirn's figures). In order to facilitate the understanding of the phenomenon, I have represented in Fig. 3 the particles of minium by large black dots 35, and the particles of sulphur by small white circles 34. 35 If negative electric charges are deposited on the wall, sulphur dust particles 36 will adhere at the corresponding point. It suffices to illuminate these material particles in order to obtain an image of the televised subject which will not only 40 be clear but also continuously mobile; for as a matter of fact, these charges tend to disappear, as a result of the slight conductivity of the wall 36, and the dust particles have the tendency to reassume their travel within the enclosure, where 45 they are subjected to continuous churning.

I have shown at 37 the container for the powder mixture, 38 is the fan which takes care of the churning of the air and of the propulsion of the dust particles, 39 is the rotor, also within the 50 enclosure, which drives the fan, and 40 is the electric stator connected to an alternating-current supply line. The powdered particles follow a closed circuit due to the canal 44. The light source 41 illuminates the back of the cathode-ray oscilloscope, which is preferably silvered and concave in order to increase the luminous efficiency. The reflected rays are concentrated on the objective 42 and thence go to the screen 43. The deposit of opaque material particles at points 60 such as 36, corresponding to the scanning by the beam and to reception of television, has the effect of reproducing on the screen the continuous image of the televised subject, and to do this faithfully, both as regards size and intensity. 65

In the figures which I have given here by way of example I have assumed that the surface on which the scanning by the cathode beam took place was metallized, and that the light source as well as the objective were placed on the same 70 side of that surface (which operated by reflection), but it is evident that one can also operate by using the transparency principle, that is to say by placing the lamp and the objective on both sides of that surface respectively. 75

It goes without saying that the invention is not limited to television purposes. It can be applied to cathode oscillographs and the like apparatus, and in general to any system of scanning involving cathode ray beams.

Having described my invention, what I claim as new and desire to secure by Letters Patent is:

1. The method of projecting images, comprising the steps of developing a source of radiant energy, developing a beam of electrons, developing a source of polarized light, projecting the polarized light upon a light polarizing medium having a predetermined plane of polarization, varying the plane of polarization of the developed medium by the developed beam of electrons, and subsequently photoelectrically restoring the plane of polarization of the medium to its original plane.

2. In combination, an envelope having a transparent end wall, an electron gun to develop a beam of electrons within said envelope, a light polarizing layer mounted on the end wall, a plurality of minute photoelectric activated bodies 5 mounted on said layer, means to direct the beam of electrons upon the plurality of photoelectric activated bodies, a source of polarized light directed upon the light polarizing layer, a polarized light analyzer and optical system in register with 10 the end wall, a source of light directed upon the photoelectric activated bodies, said source being activated to emit light only during predetermined time intervals.
